COMBINED EUCHRE SCOREKEEPER AND ASH TRAY OR SIMILAR ARTICLE

Lawrence J. McKenzie, Circleville, Ohio

Application August 7, 1951, Serial No. 16,182

Term of patent 14 years

(Cl. D85—2)

To all whom it may concern:

Be it known that I, Lawrence J. McKenzie, a citizen of the United States of America, residing at Circleville, in the county of Pickaway and State of Ohio, have invented a new, original, and ornamental Design for a Combined Euchre Scorekeeper and Ash Tray or Similar Article, of which the following is a specification, reference being had to the accompanying drawing, forming a part thereof.

Fig. 1 is a perspective view of a combined euchre scorekeeper and ash tray or similar article, showing my new design;

Fig. 2 is a top plan view showing the indexing shutter partially obscuring the face of the scorekeeper; and

Fig. 3 is a side elevational view thereof.

The bottom surface of the combined euchre scorekeeper and ash tray or similar article is plain.

The dominant features of my new design are shown in solid lines in the drawing.

I claim:

The ornamental design for a combined euchre scorekeeper and ash tray or similar article, substantially as shown and described.

LAWRENCE J. MCKENZIE.
